DESIGN FOR A UTILITY BAR

Walter C. Huxel, Cincinnati, Ohio

Application April 30, 1940, Serial No. 92,038

Term of patent 14 years

To all whom it may concern:

Be it known that I, Walter C. Huxel, a citizen of the United States of America, residing at Cincinnati, in the county of Hamilton, State of Ohio, have invented a new, original, and ornamental Design for a Utility Bar, of which the following is a specification, reference being had to the accompanying drawing, forming part thereof.

Fig. 1 is a perspective view of the utility bar of the invention, showing my new design.

Figs. 2 and 3 are cross-sectional views taken on lines 2—2 and 3—3, respectively.

I claim:

The ornamental design for a utility bar, as shown.

WALTER C. HUXEL.
